BY *G. H. Strong*

HIS ATTORNEY.

UNITED STATES PATENT OFFICE.

WILLARD R. CHAMPION, OF BERKELEY, CALIFORNIA.

FIREPLACE-DAMPER.

No. 926,048.

Specification of Letters Patent.

Patented June 22, 1909.

Application filed January 2, 1909. Serial No. 470,529.

To all whom it may concern:

Be it known that I, WILLARD R. CHAMPION, citizen of the United States, residing at Berkeley, in the county of Alameda and State of California, have invented new and useful Improvements in Fireplace-Dampers, of which the following is a specification.

My invention relates to an apparatus for the control of drafts in fire-places and connecting chimneys.

It consists of a segmental arched bonnet fitted into the upper part of the fire-place, having an opening therethrough registering with the chimney-flue, and a segmental movable damper, with means for moving it to regulate the size of the draft opening.

It also comprises the combination of operating devices and details of construction which will be more fully explained by reference to the accompanying drawings, in which—

Figure 1 is a sectional elevation of a fire-place in the plane of the axis of my apparatus. Fig. 2 is a section through X—X, Fig. 25 1. Fig. 3 is a perspective view of the gate or damper, showing a means for actuating it. Fig. 4 is a similar view showing another means.

A is a fire-place of any usual or suitable construction, the top of which is preferably arched, as shown in Fig. 2, and 2 is the chimney-flue through which the products of combustion are allowed to escape.

In the arched upper part of the fire-place 35 I fit a metal cast or otherwise formed arch 3, which is suitably set into and secured to the masonry, so as to form a permanent fixture. Through this arch, and registering with the flue 2, is made an open passage 4 having a sufficient width for any chimney-flue to which the particular sized apparatus may be fitted; this passage extending horizontally, approximately from end to end of the casing 3.

45 As the flues 2 in chimneys vary in size, and the relation of the fire-place opening to the flue may also vary, it is necessary to so regulate the opening as to provide a proper draft, independent of any temporarily adjustable features. This regulation is effected by means of a plate 5 having a length substantially equal to that of the opening 4, and such a width that it extends over the top of the curved arch 3, and has 50 its edge adapted to extend across the opening 4. When it is determined what ratio

the fire-place and flue opening must bear to each other, this plate is set to leave as large an opening as is found necessary, and is then secured permanently by means of 60 bolts or other equivalent fastenings, as 6.

Within the arch is a segment 7, the length and width of which are sufficient to close the opening 4 to any desired degree. The ends of this segment have V-shaped inturned arms 65 8 which terminate in pivots 9, and the radius of these arms 8 is such that the segment 7 fits closely and moves easily within the arch 3. 10 are stops against which the segment may rest when it has been turned so as to 70 entirely close the flue opening.

Various means may be employed to adjust and hold this segment so as to expose as much or little as may be desired of the flue opening. In Figs. 2 and 4, I have 75 shown a rocker-arm 11 which is fixed to the pivot shaft 9 at one end of the device, and by means of a rod 12 connected with the free end of the rocker-arm and extending through the front of the masonry of the 80 fire-place, the segment may be moved and the opening regulated to any desired degree. In order to adjust the length of the arm so that the operating handle will fit any thickness of masonry, or disposition of the fire- 85 place, I have shown an outer extension 12^a, which by means of clips 13 is slidable upon the part 12. Thus, when the apparatus is to be set, the thickness of the masonry and the distance between the rocker-arm and the 90 front being determined, the parts 12 and 12^a are caused to slide upon each other until the proper adjustment is effected. The outer portion of 12^a has rack teeth 14 formed upon it, and a ratchet plate 15 is fitted, 95 through which the rack bar passes, and the teeth engage with the edge of the hole in the plate when the bar is allowed to drop. By lifting it, the segment may be moved to increase or diminish the size of the opening. It is desirable, however, to make this portion of the apparatus as little conspicuous as possible, and in order to do this it is preferable to extend the pivot shaft 9 through the side of the fire-place wall. In order to 105 do this effectively, an extension 9^a is bolted, or otherwise secured, to the part 9, and the ends may be flattened and looped upon each other and secured by bolts. This extension 9^a passes through a tubular sleeve 16, and 110 this sleeve again fits in an outer larger sleeve 17. These sleeves are adjustable.

each other, and are set in the masonry of the fire-place in line with the turning axis of the segment 7, and the extension shaft 9^a passes through these tubes and has fixed to 5 the outer end, a ratchet 18. A pawl 19 is adapted to engage with this ratchet, and thus retain the parts in any desired adjustment. The parts 9 and 9^a may overlap, and have clamps, as at 13, in which they are 10 slidable, as previously described. When the apparatus is set up, these overlapping shafts are lengthened or shortened, and the clamps finally fixed at the desired distance so that the ratchet-wheel 18 and its pawl will lie 15 close to the side of the masonry and be inconspicuous. By means of a handle 20 fixed to the ratchet-wheel, the latter and its connecting shafts may be readily turned, and thus swing the segment 7 to the desired 20 position to cut off or increase the flue opening; and the tubes 16 and 17 being telescoped, as shown, may readily be adjusted, so that the apparatus, being constructed of sufficient size for any fire-place, may be 25 readily adjusted to the particular one where it is to be used, without the employment of any special tools, the adjustment being within the ability of any bricklayer or chimney builder.

30 Having thus described my invention, what I claim and desire to secure by Letters Patent is—

1. The combination with a fire-place and the chimney-flue thereof, of a circular metal arch fixed in the upper part of the fire-place, having a channel registering with the chimney-flue, a permanent plate to adjust the proportions of the flue opening; a rockable segment turnable within the arch, and means 35 for independently adjusting it and regulating the flue opening.

2. The combination with a fire-place and the flue opening thereof, of a circular metal arch fixed in the upper part of the fire-place, having a channel made through it registering with the chimney-flue, means for permanently adjusting the size of said opening with reference to the fire-place and flue 45 an independently adjustable damper, said 50 damper including a circular segment having inwardly turned ends, pivots upon which the segment is turnable and forms a radius equal to the curvature of the arch, and means by which said segment may be moved to cover 55 or disclose the flue opening.

3. In an apparatus of the character described, a circular metal arch fitting the upper part of the fire-place, having a channel registering with the chimney-flue opening, a circular segment having pivots concentric with the segment and arch, means for turning the segment; said means consisting of connecting rods, and means for adjusting the length of said rods.

4. In an apparatus of the character described, a circular metal arch fitting the upper part of the fire-place, having a channel registering with the chimney-flue, a circular segment having inwardly turned ends pivoted concentric with the curvature of the arch and segment, whereby the latter may be moved to cover or disclose a portion of the flue opening, an extension of the pivot shaft, said extension having clamps and slidable upon the inner portion of the shaft, a ratchet-wheel fixed to the outer end, and a pawl engaging said ratchet to retain the segment in its adjusted position.

5. In an apparatus of the character described, a segmental arch fixed in the upper part of the fire-place, having an opening registering with the chimney-flue, a segment fitting the interior of the arch having inwardly turned ends and pivots concentric with the curvature of the arch and segment, an extendible bar and locking clamps in line with the pivot shaft, telescopic tubes through which the extension passes, said devices forming adjustments to exactly fit the apparatus to any thickness of masonry, a ratchet-wheel fixed to the outer end of the extension, lying close against the masonry and having a handle by which the shafts and damper segment may be turned, and a pawl pivoted with relation to the ratchet adapted to hold it in any desired position.

6. A damper attachment for fire-places, said device consisting of an arch having an open channel, a fixable regulating plate attached thereto, a pivoted segment substantially concentric with the arch, a device for operating the segment, and means to adjust the length of the operating device.

In testimony whereof I have hereunto set my hand in presence of two subscribing witnesses.
